APPARATUS FOR BALANCING
PROPELLER BLADES

John Squires, Hagerstown, Md.

Application July 5, 1933, Serial No. 679,135

9 Claims. (Cl. 73—51)

This invention relates to improved apparatus for balancing propeller blades which may, if desired, be employed in the practice of the method set forth in my United States Letters Patent No. 1,968,540, and particularly propeller blades of the type adapted for use in connection with aircraft, the principal objects being the provision of an apparatus of the type set forth that is simple in construction, convenient and efficient in use, and by means of which the changes necessary in a propeller blade to bring its moment into conformance with a predetermined standard may be quickly and accurately determined.

The main objects of the invention are to obviate unbalanced conditions in propellers of the type used on airplanes; to provide an improved balance testing apparatus for this purpose by the use of which corrections to be individually made in each blade of the propeller may be determined; to provide apparatus of this kind for determining what corrections are necessary for rendering identical the characteristics of propeller blades with reference to a corresponding reference plane of each so that one or more blades of a propeller may be removed and replaced without requiring the assembled propeller to be rebalanced.

Other objects of the invention are to provide an improved balance testing apparatus for propeller blades; to provide apparatus of this character which is adapted to definitely indicate, in selected units, the degree that a propeller blade is unbalanced with respect to a predetermined standard of balance; to provide means in apparatus of this kind for accurately measuring the out of balance of a propeller blade in units which can conveniently be converted to linear units that designate the change in the position of the center of mass of the blade required to bring the latter into perfect balance with a predetermined standard of balance; and to provide a blade holding member in a balance testing apparatus of the kind described for supporting a propeller blade in a manner similar to that in which it is normally held by the hub of the propeller.

The above being among the objects of the present invention, the same consists of certain novel features of construction and combinations of parts to be hereinafter described with reference to the accompanying drawing, and then claimed, having the above and other objects in view.

In the accompanying drawing which illustrates a suitable embodiment of the present invention

and in which like numerals refer to like parts throughout the several different views,

Fig. 1 is a front elevational view of a propeller of the airplane type equipped with removable propeller blades which the present invention generally relates to, a portion of the hub being broken away to illustrate the manner of securing the blade thereto. 5

Fig. 2 is an enlarged partially sectioned side elevational view of one of the propeller blades shown mounted in the propeller in Fig. 1. 10

Fig. 3 is an enlarged transverse sectional view taken on line 3—3 of Fig. 2. 20

Fig. 4 is a side elevational view of my improved propeller blade balance testing apparatus with a 15 blade of the character shown in the preceding figures mounted therein.

Fig. 5 is an enlarged side elevational view of the apparatus shown in Fig. 4, a portion only of the propeller blade being shown. 20

Fig. 6 is an end view of the apparatus shown in Fig. 5, and taken from the right hand end thereof as viewed in Fig. 5. 25

Fig. 7 is a plan view of the apparatus shown in Figs. 5 and 6. 25

Fig. 8 is a reduced side elevational view of the apparatus illustrated in Figs. 5, 6, and 7, in a vertical position.

Figs. 9, 10, and 11 illustrate the positions at which metal may be removed from the flange of 30 the blade, shown enlarged, in order to bring the final position of the flange into predetermined accordance with respect to the center of mass of the blade as determined by the apparatus illustrated in Figs. 4 to 8, inclusive. 35

The high speeds at which propellers of the type used on airplanes are rotated demand that the blades of the propeller be balanced within close limit. Thus the moment created by the mass of each blade with respect to the axis of 40 rotation of the propeller must be substantially equal. Where a propeller is provided with replaceable blades, it is extremely desirable that one blade may be removed from the propeller and replaced by another like blade without disturbing the balanced condition of the propeller. In order that removal of one blade of a propeller and subsequent replacement by another will not materially affect the balanced condition of the propeller as a whole, it will of course be obvious 45 that the moment of the new blade with respect to the axis of rotation of the propeller must be substantially identical to that of the blade which it replaces. It will also be apparent that if such a result is to be obtained means must be pro- 50 55

vided for in the production of the blades whereby each blade of a certain size and type will conform substantially exactly in moment with respect to a predetermined plane of reference with every other blade of a like size and type with which it is adapted to be matched in a propeller or which it is adapted to replace in a propeller. The present invention relates to an apparatus by means of which the moment characteristics of a propeller blade with respect to a predetermined reference plane may be quickly and accurately determined and the difference in moment between any such blade being tested and the predetermined moment desired so indicated as to enable such variations as may be necessary to be made in the blade to bring its moment into conformance with the predetermined standard.

Referring to the drawing, it will be noted that Fig. 1 illustrates a propeller including a hub structure indicated generally as at 50 and oppositely extending blades 100. In the present case each of the blades 100 is provided at its inner or root end with a peripheral flange 106 which is received within a complementary groove formed interiorly of the hub 50. Although, in the broader aspects of the present invention, the particular mode of securing the blades 100 to the hub 50 is more or less immaterial as long as the blades are provided with a radial flange or equivalent means which serves to locate them radially with respect to the axis of rotation of the propeller, for the purpose of illustration the flange 106 and its manner of engagement with the hub 50 is assumed in the present instance to be substantially the same as is indicated in my Letters Patent of the United States No. 1,897,536, for improvements in Propeller, issued February 14, 1933. In the present instance the flange 106 serves as the sole means of supporting the corresponding blade 100 in the hub 50 and is provided with an outer or tip face 196 lying in a plane perpendicular to the longitudinal axis of the blade 100 and an inner or root end face 198 of frusto-conical formation. The main body portion of the blade is of course of the usual airfoil section as illustrated in Fig. 3 having a leading edge 108, a trailing edge 110, a front or camber face 110a and a rear or flat face 110b. The grooves of the propeller hub 50 in which the flanges 106 of the blade 100 are received are accurately machined and they are accurately located at equal distances from the axis of rotation of the propeller hub.

The moment created by a blade is a function of its mass and the distance of its center of mass from the axis of rotation of the propeller and therefore changes in the moment of a blade may be produced by shifting it outwardly with respect to the axis of rotation of the propeller. In the present instance the moment arm, or distance between the axis of rotation of the propeller and the center of mass of the blade is varied by trimming off the inner and/or outer face of the flange 106 which is received in the groove of the propeller hub by an amount necessary to bring it to accordance with a fixed standard. Only the side faces 196 and 198 of the flange 106 of each blade is engaged by the walls of its groove and thus either the inner or outer side faces of the flange may be relied upon to determine the location of the center of mass of each blade from the axis of rotation of the propeller. In practice the flange 106 initially is intentionally made thicker than the groove of the hub in

which it is to be received so as to permit corrections to be made in the location of the center of mass of the blade with respect to the flange, and the outer side face 196 of the flange 106 initially usually occurs in too close proximity to the center of mass to allow the blade as originally formed to balance the standard moment differential of the testing apparatus. As the blank from which the blade is formed is machined accurately both internally and externally, as specifically brought out in my co-pending application for Letters Patent of the United States for improvements in Propeller blade and method of producing same, filed July 5, 1933, and serially numbered 679,133 the distribution of weight in all blades of the same size and type is substantially the same and therefore only slight corrections in the location of the centers of mass of the blades are required.

In Figs. 4 to 8, inclusive, is illustrated an apparatus for equalizing the moments of the blades of a propeller with respect to the axis of rotation thereof. This apparatus includes a block 432 of substantial weight having a tapering dovetailed groove 434 centrally disposed at one end which extends between and is open at the respectively opposite sides 436 and 438 of the block 432, for receiving the flange 106 of a propeller blade. The groove 434 is undercut in parallelism with the side edges thereof, as best shown in Fig. 5, the undercut portion being shaped in section complementary to the section of the flange 106 so as to removably receive the flange therein and thereby enable the blade to be secured relative to the block 432 without contact of the block with the shank of the blade.

Formed on the respectively opposite sides 436 and 438 of the block 432 are trunnions 440 and 442 which rest upon the horizontal knife edge supports 444 and 446 respectively and pivotally support the block. The trunnions 440 and 442 are in alignment with each other but they are in misalignment with the center of mass of the block 432. They are located in closer proximity to the end of the block in which the flange receiving groove 434 is formed than to the opposite end of the block. This arrangement sets up a moment differential between the portions of the block on respectively opposite sides of the axis of the trunnions 440 and 442 which is of a predetermined amplitude. The trunnions are equidistant from the top and bottom of the block and their axis lies in the central plane passing through the center of the groove 434.

A graduated bar 448 is provided on one side of the block 432 substantially in the plane passing through the axis of the trunnions 440 and 442 and the horizontal center line of the groove 434. The graduated bar 448 is offset slightly from the side of the block 432 by means of supports 449 arranged preferably at the ends of the graduated bar 448 so as to provide room for a weighted slide 450 which straddles the graduated bar 448 and may be moved longitudinally thereon. When moved toward its extreme left hand position in Fig. 5 the weighted slide 450 augments the moment differential of the block 432. When a propeller blade is mounted in the groove of the block the weighted slide 450 may be moved to the right or to the left so as to balance the propeller blade supported by the block. The scale 451 on the bar 448 may be suitably arranged to conveniently indicate changes necessary in the flange of the propeller blade to bring

its moment to the desired standard. A convenient arrangement is to graduate the scale in tenths of an inch and to provide a slide 450 having a weight equal to 1/100th of the weight of the blade. With this arrangement each graduation on the scale will correspond to 1/1000th of an inch variation in the location of the face of the flange 106. Thus when with the blade mounted in the balancing apparatus it is found that the weighted slide 450 has to be moved one graduation on the scale in order to produce accurate balancing it indicates that the face of the flange 106 must be trimmed 1/1000th of an inch in order to produce the desired static moment in the blade.

The weight of the block 432 and the location of the trunnions 440 and 442 thereon may be difficult to predetermine exactly and accurately. In order to aid in adjusting the moment differential and produce the condition which is desired for testing the blade, there may be provided means in the block 432 for adjusting its moment. This may conveniently consist of a bolt 452 or the like threaded into a seat 453 in the end of the block 432 opposite the groove 434. The seat 453 preferably lies in the plane passing through the axis of the trunnions 440 and 442 and the center line of the slot 434. It will be perceived that the bolt 452 may be moved in or out of its seat 453 to produce the correcting effect desired.

The description of the balancing apparatus so far relates to the use of the apparatus when the propeller is in a horizontal position and such use is important as has been indicated. Since the propeller, the adjustable bolt 452, the weight 450 and the bar 448 are all symmetrically arranged with respect to the axis of the trunnions 440 and 442, it is possible to turn the apparatus on the knife edges 444 and 446 so that the propeller extends in a vertical direction as indicated in Fig. 8. Since the face of the flange 106 is at right angles to the axis of the propeller, the apparatus should remain at rest with the axial line of the blade at the tip thereof directly under the axis of the trunnions 440 and 442, and a trial of the balancing apparatus in the vertical position thus may be a convenient method of assuring that the center of gravity of the propeller is actually in the longitudinal axis of the blade.

If a blade, upon testing, exactly balances the standard moment differential of the apparatus, then the root end side face of the flange 106, including the beveled face 198, and the inner extremity of the blade is trimmed, as illustrated in Fig. 9, so as to produce a flange 106 of predetermined thickness without changing the location of the tip end side face 196 of the flange. If the cut is required at the tip end side face 196 of the flange 106 and is sufficient to reduce the thickness thereof to its predetermined thickness, then the root end side face 198 of the flange 106 is left unaltered, as indicated in Fig. 10, except perhaps to more accurately dimension the beveled face 198. These two cases are not usual ones. Generally the tip end side face 196 is trimmed off sufficiently to bring the blade into exact balance with the moment differential of the apparatus and then the root end side face 198 and inner extremity of the blade is machined slightly, as indicated in Fig. 11, to produce a flange 106 of predetermined thickness and shape to suit the hub with which it is to be used.

It is, of course, entirely possible to employ the

root end side face 198 of the flange 106 as the reference plane for determining the location of the center of mass of a blade from the axis of rotation of a propeller hub in which the blade is to be mounted. Under these circumstances the root and side face 198 of the flange 106 is machined first during modification of the flange to bring the blade into balanced relationship with a standard moment differential, and then sufficient metal is removed from the tip end side face 196 of the flange 106 to bring the flange to a predetermined thickness.

In either of the above cases, whichever face of the flange 106 is employed as a reference plane in determining the location of the center of mass of the blade, in subsequently reducing the flange to its desired thickness and final location, the following procedure is preferably followed. The blade is rotated between suitable centers in a lathe or other suitable machine tool, and the centers are accurately located preferably on the longitudinal axis of the blade passing through its center of mass. With the blade thus supported, a suitable tool (not shown) is employed to remove the required metal from the flange 106 to bring it to final shape, size and location. Preferably a grinding tool will be used as thus a more delicate adjustment may be procured. This method of supporting the blade for finishing the flange insures that the plane of the flange 106 will be normal to a line passing centrally through and axially of the flange, and also through the center of mass of the blade.

It will be apparent from the above that by the method disclosed herein it is possible to form any number of propeller blades so that their centers of mass will all be located at such points that each blade will have the same static moment about the center of rotation of the propeller of which they are to form a part.

Formal changes may be made in the specific embodiment of the invention described without departing from the spirit and substance of the broad invention, the scope of which is commensurate with the appended claims.

I claim:

1. Apparatus for balancing propeller blades including a pivotally mounted member having a standard moment differential on one side of its pivotal axis, means on said member for receiving a flange of a propeller blade and detachably supporting the latter on the other side of said pivotal axis with its longitudinal axis in a plane substantially normal to the pivotal axis of said member, including a reference surface engageable with one side of said flange for predetermining the distance of said side of said flange from said axis and including means for positively urging said flange into engagement with said reference surface, and means for varying the moment differential of the respectively opposite sides of said member by known increments so as to determine the amount the moment of said blade varies from said standard moment, said last mentioned means including a scale and a shiftable weight constructed, arranged and calibrated so as to indicate in units of thickness, the correction required in the thickness of said flange to bring said blade to said predetermined standard.

2. Apparatus for balancing propeller blades including a weighty member, a pair of co-axial trunnions, one on each side of said member located in misalignment with its center of mass, means coacting with the said trunnions for

- pivots supporting said member, means at the end of said member which is closer to said trunnions, having a channel for receiving the flange of the propeller blade so as to detachably support the latter, said channel having a side wall adapted to predetermine the distance between a side of said flange and the axis of said trunnions and having a relatively inclined wall for holding flanges of different thicknesses in engagement with said first mentioned wall, and mechanism at the other side of the trunnions from the means for supporting the blade for balancing said blade including graduated means for determining variations in the moment of said blades.
3. Apparatus for balancing propeller blades including a weighty member, a pair of co-axial trunnions, one on each side of said member located in misalignment with its center of mass, means co-acting with said trunnions for pivotally supporting said member, means at the end of said member which is closer to said trunnions for receiving a flange of a propeller blade and detachably supporting the latter, said means including a pair of relatively inclined, opposed surfaces for positively positioning a reference surface on said flange at a predetermined distance from the axes of said trunnion, and mechanism at the other side of the trunnions from the means for supporting the blade in a plane including the axes of said trunnions and the axis of the supported blade for balancing said blade including graduated means for determining variations in the moment of said blades.
4. Apparatus for balancing propeller blades, including a pair of supports, a block pivotally mounted on said supports having a larger portion of its mass on one side of its pivotal axis than on the other, means on the lighter end of said block for receiving a peripheral flange of the hub end of a propeller blade and having a reference surface engageable with one side of said flange and an element for urging blades of different thicknesses into firm engagement with said reference surface for predetermining the location of said side of said flange with respect to the pivotal axis of said block, and variable balancing mechanism including a scale which is calibrated in units that are proportional to units of thickness of said flange for determining the variation in the thickness of said flange required to correct the moment of said blade.
5. Apparatus for balancing propeller blades including a pivotally mounted block having a standard moment differential about its pivotal axis, that end of said block of lower moment being provided with a tapering dove-tailed groove for receiving a flange of the hub end of a propeller blade so as to predetermine the location of a side of said flange with respect to the pivotal axis of said block, and variable balancing mechanism on said block for determining the difference in the moment of said blade and said standard moment differential and including a scale calibrated to indicate the change in the thickness of said flange required to shift the center of mass of said blade sufficiently to equalize the moment of said blade with the moment differential of said block.
6. Apparatus for balancing propeller blades including a pivotally mounted block having a standard moment differential about its pivotal axis, means on the end portion of said block
- of lower moment for receiving a flange of the hub end of a propeller blade including a reference surface engageable with said flange for predetermining the location of a side of said flange from said axis and including means for urging a surface of said flange into engagement with said reference surface, and variable balancing mechanism on said block for determining the difference in the moment of said blade and said standard moment differential and including a scale having graduations thereon that are proportional to linear units of thickness of said flange for determining the change in the thickness of said flange required to shift the center of mass of said blade sufficiently to equalize the moment of said blade with said standard moment differential.
7. Apparatus for balancing propeller blades including a pivotally mounted block having a standard moment differential about its pivotal axis, the end portion of said block of lower moment being provided with a tapering dove-tailed groove for receiving a flange of the hub end of a propeller blade so as to predetermine the location of said side of said flange with respect to said axis, a scale on said block, a weight slideable on said scale in a direction parallel with the supported propeller blade and approximately equally disposed on opposite sides of a plane including the pivotal axis of said block and the axis of said blade, said weight cooperating with said scale to indicate the unbalance of said blade with respect to said standard moment differential.
8. Apparatus for balancing propeller blades including a pivotally mounted block having a standard moment differential about its pivotal axis, means on the end portion of said block of lower moment for receiving a flange of the hub end of a propeller blade, said means being so constructed and arranged as to predetermine the location of a side of said flange with respect to the pivotal axis of said block, a scale on said block, a weight slideable on said scale in a direction parallel with the supported propeller blade and approximately equally disposed on opposite sides of a plane including the pivotal axis of said block and the axis of said blade, said weight cooperating with said scale to indicate the unbalance of said blade with respect to said standard moment differential.
9. Apparatus for balancing propeller blades including a pivotally mounted block having a standard moment differential about its pivotal axis, means on that end of said block of lower moment for receiving arcuately spaced portions of a flange of the hub end of a propeller blade so as to detachably support the latter in perpendicular relationship to said pivotal axis and including reference surfaces engageable with arcuately spaced portions of a side of said flange for predetermining the location thereof with respect to said axis, and variable balancing mechanism on said block for determining the difference in the moment of said blade and said standard moment differential and including a scale calibrated to indicate the change in the thickness of said flange required to shift the center of mass of said blade sufficiently to equalize the moment of said blade with the moment differential of said block.

JOHN SQUIRES.
